MULTIPLE NEEDLE SEWING MACHINE

Walton D. Suenders, Berwyn, Ill., assignor to
Union Special Machine Company, Chicago, Ill.,
a corporation of Illinois

Application June 18, 1930, Serial No. 462,031

7 Claims. (Cl. 112—167)

The invention relates to new and useful improvements in sewing machines, and more particularly to a multiple needle sewing machine.

In a multiple needle sewing machine for forming independent lines of stitches it is often desirable to shift the position of the needles and loopers so as to produce lines of stitches which are of different spacing.

An object of the present invention is to provide means whereby the position of the loopers may be shifted and fixed in predetermined positions on the support therefor, and wherein the operating means for said loopers may be adjusted to a predetermined extent so that the timing of the loopers relative to the needles may be maintained in their different set positions.

A further object of the invention is to provide a gaging means associated with each looper which may be utilized for determining and holding the looper with which it is associated in predetermined set positions.

A still further object of the invention is to provide a machine wherein the loopers are shiftable from one set position to another, and wherein the operating means for said loopers may be adjusted to a predetermined extent so that the timing of the loopers relative to the needles may be maintained in their different set positions.

These and other objects will in part be obvious and will in part be hereinafter more fully disclosed.

In the drawings which show by way of illustration one embodiment of the invention:—

Figure 1 is a front view of a machine embodying the invention with parts broken away to show the operating mechanism in rear thereof;

Fig. 2 is a plan view of the parts of the machine beneath the work support with the feed dog broken away to show the looper operating mechanism beneath the same;

Fig. 3 is an enlarged front view of the looper support, the loopers mounted thereon, and the means connected to the loopers for oscillating the same;

Fig. 4 is a sectional view on the line 4—4 of Fig. 3;

Fig. 5 is a sectional view on the line 5—5 of Fig. 3, and

Fig. 6 is an enlarged front view of the gaging devices and showing the means with which they cooperate in the positioning of the loopers.

The invention is directed to a multiple needle sewing machine wherein the needles and associated loopers form independent lines of stitches. It is often desirable to change the gage of the ma-

chine, that is the spacing of the lines of stitches. In order to accomplish this, the needles are laterally shiftable upon the needle head, and the loopers are likewise laterally shiftable upon the supporting member therefor. The present invention has to do particularly with the gaging means for positioning the loopers in predetermined set positions for a different spacing of the lines of stitches. The loopers are mounted on independent carriers, and each carrier is mounted on a stud which is shiftable on the support which carries the stud. Associated with each looper is a gaging device which determines a desired set position for the looper. This gaging device is adjustable or shiftable so that it may be used for determining several settings of the looper with which it is associated. The loopers are oscillated on their supports by a common link which is connected to a bar that joins the loopers. Each looper has a ball stud, and the bar is provided with two independent heads which engage the respective ball studs. One of these heads is adjustable on the supporting bar therefor, and means is provided for setting the head in predetermined positions so that the extent to which the means for oscillating the loopers is adjusted is a predetermined extent which will insure that the loopers will be properly maintained in their timing with respect to the needles with which they cooperate.

Referring more in detail to the drawings the invention is shown as applied to a sewing machine which includes a supporting bed 1 carrying a work support 2. Mounted on the bed 1 is a standard 3 carrying an overhanging arm 4. A needle bar 5 reciprocates in suitable bearing lugs 6, 6 at the outer end of the overhanging arm 4. The needle bar is reciprocated by means of a needle lever 7 pivoted at 8 and oscillated by an eccentric strap 9 cooperating with an eccentric on the main shaft 10. At the lower end of the needle bar 5 is a needle clamping head 11. Mounted in this clamping head 11 are two needles 12 and 13. The material is held on the work support by a presser foot 14, and is fed across the work support by a feed dog 15. Cooperating with the needle 12 is a looper 16, and cooperating with the needle 13 is a looper 17. The looper 16 is mounted on a looper carrier 18. The looper carrier 18 is in turn mounted for oscillation on a supporting stud 19 of the usual character. The looper 17 is mounted on a carrier 20 which in turn is mounted for oscillation on a supporting stud 21. The supporting studs 19 and 21 are mounted on a supporting yoke 22 which is of the usual character, and this yoke carries a shaft 23 pro-

vided with a forked arm 24 cooperating with an eccentric on the main shaft 10. This eccentric and forked arm impart a rocking motion to the yoke 22, and this gives to the loopers their needle 5 avoiding movement. The loopers are oscillated by means of a link 25 which is connected to a bar 26, and the bar 26 is in turn connected to the two looper carriers. The link 25 is pivoted at 27 to an oscillating member 28 which in turn is connected to a link 29 attached at 30 to the needle lever extension 31. This oscillating mechanism for the loopers is of the usual construction. As the needle lever oscillates it not only reciprocates the needle bar but it will also impart through the 15 link 26 oscillations to the two looper carriers.

The stud 19 on which the looper carrier 13 is mounted extends through a slot 32 in the supporting yoke 22. Said stud is provided with an integral collar 33, and a nut 34 on the end of the 20 stud clamps the stud in its set positions on the supporting yoke. The stud 24 extends through a slot 35. This stud is provided with an integral collar 36 and with a nut 37 for holding the stud in set positions on the supporting yoke. Associated 25 with each looper is a gaging device for aiding in setting of the loopers in predetermined positions for oscillation. Mounted on the stud 19 between the collar 33 and the supporting yoke is a gaging device 38. This gaging device is in 30 the form of a disk. It is freely mounted on the stud so that it may be turned when the nut 34 is released. The disk, as shown in the drawings, is provided with three gaging recesses 39, 40 and 41. These gaging recesses as shown are 35 segmental in shape, and are adapted to contact with a gaging post 42. This gaging post, as shown in the drawings, is in the form of a large headed screw, which is threaded into the yoke support 22. The screw has a relatively large cylindrical 40 head. The recesses are shaped to fit the gaging post 42. These recesses are formed so that they are spaced radially from the center of the stud 19 at different distances. In Fig. 6 of the drawings the disk is shown in full lines positioned so 45 that the recess 39 makes contact with the peripheral surface of the head of the gaging screw or post 42. When so positioned then the nut 34 is turned down so as to clamp the looper in this set position. By loosening the nut and turning 50 the disk any one of the recesses may be brought into contact with the gaging post and thus it is that this looper supporting stud 19 may be shifted to three different predetermined set positions. Through the aid of this gaging disk the looper 55 can be shifted from one setting to another and always brought back to the same set position. Cooperating with the stud 24 is a similar gaging disk 43 which is provided with a recess 44 corresponding to the recess 39 as to its distance from 60 the center of the supporting stud 24; also a recess 45 corresponding to the recess 40 and a recess 46 corresponding to the gaging recess 41. These recesses 44, 45 and 46 are adapted to be brought into contact with the same gaging screw or post 42. It will be seen that means has been provided 65 for either shifting one of the loopers or shifting both of the loopers from one predetermined set position to another predetermined set position. This is accomplished by gaging devices associated 70 with each looper support, and functioning to determine each set position of the loopers.

The bar 26 which oscillates the loopers is provided with a ball stud 47 with which a head 48 on the end of the link 25 makes engagement. The 75 looper carrier 16 is provided with a ball stud 49.

A head 50 is secured to the bar 26 and is adapted to cooperate with this ball stud 49. This head 50 is adjustably mounted on the bar 26 so that it may be shifted in a direction lengthwise of the bar. To this end the bar is provided with a slot 51. A clamping bolt 52 passes through the slot, and is threaded into the head 50 which cooperates with the ball stud 49. The outer face of the bar 26 is provided with three vertical grooves or recesses 53, 54 and 55. Mounted on the bolt 52 is 10 a collar 56 which is provided with a rib 57. This rib 57 is adapted to engage any one of the grooves or recesses 53, 54 or 55. When the looper support 19 is shifted from its present setting at the left of the supporting yoke 22 to the next set position, then the bolt 52 is released and the rib 57 is shifted to the groove or recess 54. By this shifting of the position of the head 50 the connection between the looper carrier and the stud 47 has been shortened to precisely the same extent as the stud has been shifted on the yoke support. Therefore, the looper in its new setting with the new setting of the needle will retain its original timing relative to the reciprocation of the needle. 15

The looper carrier 20 is provided with a ball stud 58. A head 59 cooperates with this ball stud, and is secured to the bar 26 by means of a bolt 60. The bar 26 is slotted as indicated at 61, and this bolt 60 passes through this slot. This enables the head 59 to be shifted endwise of the bar. A similar setting means may be provided for this head if desired. Each head 50 and 59 has a rib and groove connection with the bar which prevents these heads from turning on their support 20 bolts. Means has been provided for positively shifting the head 59. This means includes a link 62 which has an opening therethrough to receive the bolt 60. The other end of the link has an opening therethrough which receives an eccentric 30 end portion 63 of a knurled collar 64. A screw 65 holds this knurled collar in set position. By loosening the screw 65 the knurled collar may be turned, and this through the operation of the eccentric portion 63 will move the link 62 endwise. 35 The bolt 60 is of course first released so that it can be shifted and then the turning of the knurled collar will positively shift the bolt and the head 59 with which it is connected in one direction or the other and retain it in its set position. 40

The link 25 is connected to the heads at the ends thereof by right and left hand threads 25^a and 25^b. By turning this link the position of the loopers relative to the needle lever extension may be varied and in this way the timing of the loopers change. In the setting up of the machine there are sometimes inaccuracies in the dimensions of the loopers and the shifting means including the knurled collar 64, described above, enables a setting of the loopers to be made so that both looper points will be properly positioned for the needles of a predetermined gage. When it is desired to change the timing of the loopers this is accomplished by turning the link 25. This brings about the initial setting of the loopers and the timing thereof. When it is desired to change from one gage to another, then the mechanism described above may be utilized for shifting the left-hand looper and the connection to the operating means therefor. Not only is each looper provided with its gaging means for setting the position in which it is to oscillate, but means is also provided for varying the connection of the respective looper carriers to the means which imparts oscillations thereto so that the timing of the loopers may be 45 50 55 60 65 70 75 80 85 90 95 100

maintained with respect to the needles with which they are associated in their various set positions.

It is obvious that minor changes in the details of construction and the arrangements of the parts 5 may be made without departing from the spirit of the invention as set forth in the appended claims.

Having thus fully described my invention what I claim as new and desire to secure by Letters 10 Patent, is:—

1. In a sewing machine, a needle, a looper, an oscillating looper carrier, means associated with said oscillating looper carrier permitting the same to be shifted bodily to one of a predetermined series of set oscillating positions, means for imparting oscillations to said carrier, and means for permitting said oscillating means to be adjusted and for predetermining the adjustment thereof to one of a similar series of predetermined set 15 positions so as to maintain the timing of the looper and the needle.

2. In a sewing machine, a plurality of needles, a looper for each needle, a looper carrier for each looper, means associated with each looper carrier 20 permitting either of said carriers to be shifted bodily to one of a predetermined series of set oscillating positions, means for imparting oscillations to said carriers, and means for permitting said oscillating means to be adjusted to one of a similar series of predetermined set positions so as to maintain the timing of each looper and the needle associated therewith.

3. In a sewing machine, a needle, a looper, a looper carrier, a supporting stud on which said looper carrier is mounted, a supporting yoke to which said stud is attached, means permitting said supporting stud to be shifted on said supporting yoke, a gaging disk mounted on said stud and having a plurality of recesses arranged 35 at different distances from the center of the stud, and a gaging post carried by the yoke with which said disk cooperates for the placing of the looper in predetermined set oscillating positions.

4. In a sewing machine, a plurality of needles, a looper for each needle, a looper carrier for each looper, a supporting yoke for said looper carriers, each carrier being mounted on the supporting yoke so that it may be adjusted lengthwise of the yoke, means associated with each looper carrier whereby said looper carrier may be placed in 45

predetermined set oscillating positions on said yoke, said last named means including a gaging disk associated with each carrier, and a gaging post mounted on the supporting yoke, each disk having a series of recesses adapted to receive the post, said recesses being set at different distances from the center of the looper carrier with which it is associated.

5. In a sewing machine, a plurality of needles, a looper for each needle, a looper carrier for each looper, a supporting yoke for said looper carriers, each carrier being mounted on the supporting yoke so that it may be adjusted lengthwise of the yoke, means associated with each looper carrier whereby said looper carrier may be placed in predetermined set oscillating positions on said yoke, 10 means for oscillating said looper carriers including a bar, a ball stud attached to each carrier, heads cooperating with the respective ball studs on the carriers, and means for adjustably securing 15 said heads to the bar so that said heads may be shifted lengthwise of the bar.

6. In a sewing machine, a plurality of needles, a looper for each needle, a looper carrier for each looper, a supporting yoke for said looper carriers, each carrier being mounted on the supporting yoke so that it may be adjusted lengthwise of the yoke, 20 means associated with each looper carrier whereby said looper carrier may be placed in predetermined set oscillating positions on said yoke, means for oscillating said looper carriers including a bar, a ball stud attached to each carrier, heads cooperating with the respective ball studs on the carriers, and means for adjustably securing 25 said heads to the bar so that said heads may be shifted lengthwise of the bar, and means whereby one of said heads may be placed in predetermined set positions.

7. In a sewing machine, a plurality of needles, a looper for each needle, a looper carrier for each looper, means associated with each looper for permitting either of said carriers to be shifted bodily to one of a series of predetermined set positions, an oscillating device, independent means for connecting each looper carrier to said device, 40 and means for permitting the independent adjustment of said connecting means to similar positions so as to maintain the timing of each looper with the needle associated therewith.

WALTON D. SUENDERS. 50
